PIPE BORE CLEANER APPARATUS

Hubert R. Crane, Los Angeles, Calif.

Application June 2, 1942, Serial No. 445,445

2 Claims. (Cl. 15—104.06)

This invention is apparatus for cleaning the bores of various installed conduits; as for example extensive underground water service systems.

There has been heretofore no simple, low-cost, practical, highly effective and economical tool and apparatus combination and method whereby to clean out and maintain in a free flowing condition the bore of water systems (in particular) and it is very common to have to resort to costly-labor digging and plumbing operations to expose, remove, clean and re-install or re-place the conduit elements by operation upon relatively short sections of a given system. It is an object of the instant invention to provide means for eliminating all of the above objectionable factors and to provide an extremely simple and inexpensive tool and apparatus and installation limbs for greatly facilitating the initial cleaning and thereafter the maintenance of the given system in a clean condition.

While the present disclosure resorts to the employment of some old and well known parts and means these are here shown in a new and highly useful combination in this particular art, and the present advance in this art further involves the accomplishment of the cleaning process by a distinctive and new set of steps concerning the manner in which a given fluid, say water in a service system, is run in the installed, new combination and the peculiar use of given implements.

The invention consists in certain advancements in this art as set forth in the ensuing disclosure and having, with the above, additional objects and advantages as hereinafter developed and whose constructions, combinations and sub-combinations and details of means, will be made manifest in the following description of the here-with illustrative embodiments; it being understood that modifications, variations and adaptations may be resorted to within the scope, spirit and principle of the invention as it is more directly claimed presently.

Figure 1 is a sectional, longitudinal elevation of a portion of a water pipe system disclosing a new, installed double or duplex Y and manhole tap set-up as in use by the initial bore cleaning set of the novel means.

Figure 2 is a view of the same set-up as arranged for and in use by the second or next cleaning step.

Figure 3 is a broken side elevation of a water and tool deflector and guide forming a removable element of the operating apparatus.

There is shown an old, installed or underground

water main M having a conventional shut-off gate valve V1 suitably adjacent to a conventional installed pipe line limb or Y with a relative access manhole and cover C. Suitably remote downstream from the valve V1 is another shut-off valve V2 or other suitable device whereby the water may be stopped at will.

Water mains have lengths of many miles in relative supply systems and it is an object of this invention to provide for the safe, ready and effective cleaning of as much as a mile section or more at one operation.

In carrying out the new combination there is introduced into the main a second Y limb Y2 in quite close relation to the above mentioned Y at Y1; the branches of the two Y's being at opposite angular directions, the first upstream or toward direction of water flow from the source feeding the main and the second inclined downstream or in the direction of water flow. Each of the Y limbs has a short pipe section as 2 and 3 with bell mouths adapted to receive any suitable type of closure or plug P, and these are accessible by way of manholes C thereat in the ground or other surface according to the place of system installation.

Now assuming that it is desired to clean out 5000 feet of the main M upstream from the valve V1 this is closed and if there is not already installed a Y limb Y1 then one is now installed and its plug P is set tight to prevent discharge of water when, later, the valve V1 is opened. If and when the limb Y1 is in place the new limb Y2 is installed and pointed downstream and its mouth is let open. A suitable means which will both substantially stop flow and will form a deflecting guide for any suitable scraping tool, such as a flexible, backbone go-devil S, is inserted into the second limb Y2 to close its trunk bore 4 (which is an axial continuation of the bore of the main M). Such means here consists of a simple, semicylindrical shovel or scoop D fitting the Y bore and the bottom of the bore 4 to close it and having a hook part D' to removably retain it in place at the crotch of the Y Y2.

Subsequent to closing the limb Y1 by its plug P the appropriate scraper S is pushed into the far upstream end of the portion of the main M; the valve V1 being, at the time, shut, and the guide or deflector D being in place and the downstream Y Y2 being open so that water will be directed to the relative or second manhole.

The valve V1 is now opened and the head of water will react on the interposed scraper S and drive it toward the said valve with sufficient

power to scrape and clean the bore surface; the cuttings being conveyed down to the opened Y limb Y2 by water which is allowed to escape past the scraper S. Since the deflecting guide and stop D closes the bore of the main thereat and since the upper Y limb Y1 is closed by its plug P finally the scraper S is driven up to and up through and out of the second limb Y2. If this is assumed to be the first cleaning operation of this given section of the main it will be seen that after the duplex or double Y limb combination Y1 and Y2 has been installed (at its first cost), then, thereafter, the said section of the main can be often cleaned at but only the cost of labor.

Having completed the upstream section of the main M as to the valve V1 this latter is again closed, the guide D is removed, a plug P is set in the lower Y limb Y2, the plug P is dislodged from the limb Y1 to open this limb and the lower valve V2, which stood closed during the operation of cleaning the first section of the main, is now opened.

The scraper S having now been discharged or pulled from the limb Y2 is inserted into the upper limb Y1, Fig. 2, and adjusted in the bore of the main M so that as the valve V1 is now opened, water will catch the interposed scraper S and drive it down toward the open valve V2 and that section of the main M leading to the valve V2 will be cleaned and scraped, the limb Y1 having been again plugged as soon as the scraper S was properly set in the junction with the main.

While the two limbs Y1 and Y2 are arranged at opposite inclinations in the main they are nevertheless duplex and constitute a double and are indeed duplicates—just in reversed arrangement.

It is to be understood that the downstream valve V2 either may or may not be used if it is in place in a system, and that the method may be

practiced even in the absence of such a valve since the scooping and diverting guide D will effectively shunt the stream of water to the open downstream Y limb and will cause the ejection of the scraping tool when it comes against the guide.

A suitable type of scraper is shown in U. S. Letters Patent No. 2,099,723.

What is claimed is:

- 10 1. Apparatus for the cleaning and scraping of fluid conveying conduits, comprising in combination, a downstream effect Y limb in a given conduit, an appropriate scraping tool for the bore of the conduit and which is propulsive by the bore fluid, and a bore choking device consisting of a short semicylindrical scoop of an external diameter approximating that of the Y limb lateral to make an elbow extension of the cylindrical bore thereof at the conduit axis forming a guide whereby to direct the said tool into the outlet of the said limb, while the tool is fluid driven; the said choke being adapted to be telescoped down the said limb into effective position at the conduit bore while the limb is in situ.
- 15 2. In apparatus of the class described for choking off a conduit at a Y limb in a sunken system; a scooping guide of semicylindrical cross-section to form a continuation of the Y lateral branch bore and; designed and constructed of a size and shape whereby to be telescoped into and from the head of the limb in situ while the head of the limb is uncovered and whereby to eliminate removal of the limb or opening of the main conduit for placement of the guide or its removal and the guide having a holding lug on its bottom surface at a slight distance back from the upper end of the guide for interlocking against a crotch edge of the said limb.
- 20 3. In apparatus of the class described for choking off a conduit at a Y limb in a sunken system; a scooping guide of semicylindrical cross-section to form a continuation of the Y lateral branch bore and; designed and constructed of a size and shape whereby to be telescoped into and from the head of the limb in situ while the head of the limb is uncovered and whereby to eliminate removal of the limb or opening of the main conduit for placement of the guide or its removal and the guide having a holding lug on its bottom surface at a slight distance back from the upper end of the guide for interlocking against a crotch edge of the said limb.
- 25 4. In apparatus of the class described for choking off a conduit at a Y limb in a sunken system; a scooping guide of semicylindrical cross-section to form a continuation of the Y lateral branch bore and; designed and constructed of a size and shape whereby to be telescoped into and from the head of the limb in situ while the head of the limb is uncovered and whereby to eliminate removal of the limb or opening of the main conduit for placement of the guide or its removal and the guide having a holding lug on its bottom surface at a slight distance back from the upper end of the guide for interlocking against a crotch edge of the said limb.
- 30 5. In apparatus of the class described for choking off a conduit at a Y limb in a sunken system; a scooping guide of semicylindrical cross-section to form a continuation of the Y lateral branch bore and; designed and constructed of a size and shape whereby to be telescoped into and from the head of the limb in situ while the head of the limb is uncovered and whereby to eliminate removal of the limb or opening of the main conduit for placement of the guide or its removal and the guide having a holding lug on its bottom surface at a slight distance back from the upper end of the guide for interlocking against a crotch edge of the said limb.
- 35 6. In apparatus of the class described for choking off a conduit at a Y limb in a sunken system; a scooping guide of semicylindrical cross-section to form a continuation of the Y lateral branch bore and; designed and constructed of a size and shape whereby to be telescoped into and from the head of the limb in situ while the head of the limb is uncovered and whereby to eliminate removal of the limb or opening of the main conduit for placement of the guide or its removal and the guide having a holding lug on its bottom surface at a slight distance back from the upper end of the guide for interlocking against a crotch edge of the said limb.
